UNITED STATES PATENT OFFICE

LOUIS SEUTTER, OF MILWAUKEE, WISCONSIN, ASSIGNOR TO THE KIEL FURNITURE COMPANY, OF MILWAUKEE, WISCONSIN, A CORPORATION OF WISCONSIN

RADIOTABLE

Application filed August 1, 1929. Serial No. 382,751.

This invention relates to improvements in radio tables.

It is one of the objects of this invention to provide a radio table, in which a complete radio apparatus and speaker may be so concealed that the table will have the appearance of being an ordinary occasional table and in which, in spite of the concealed position of the speaker, the sound vibrations will be permitted to come forth therefrom in such a manner as to give true tone value.

A further object of this invention is to provide a radio table in which means is provided for deflecting the sound vibrations emitted from the rear of the speaker so that said vibrations will not interfere with or neutralize the vibrations coming from the front of the speaker to impair the tone value.

A more specific object of this invention is to provide an improved radio table in which the apparatus and speaker are mounted upon a novel type of baffle board, the said baffle board having a fence surrounding a portion thereof, the said fence decreasing in height toward the sides to direct the sound vibrations emitted from the rear of the speaker toward openings provided beneath the table top, on each side of said baffle board.

A further object of this invention is to provide a radio table in which resilient feet are provided on which the receiver is adapted to be mounted, the said resilient feet preventing vibrations from the speaker from impairing the operation of the receiver and vice versa, and said feet further being adapted to elevate the receiver so that a portion of the speaker may extend therebeneath, the latter feature permitting a more compact construction.

A further object of this invention is to provide a radio table in which an opening is provided between the table frame and the top to permit sound vibrations to emerge therefrom, and also to permit a complete circulation of air beneath the table to carry away heat generated by the receiver.

A further object of this invention is to provide a radio table which is simple in construction, attractive in appearance, and well adapted for the purpose described.

With the above and other objects in view, the invention consists of the improved radio table, and all its parts and combinations, as set forth in the claims, and all equivalents thereof.

In the accompanying drawings, in which the same reference characters designate the same parts in all of the views:

Fig. 1 is a perspective view of the improved table, the front panel being swung downwardly to permit access to the operating knobs;

Fig. 2 is a top view of the table, with the greater part of the table top removed to show interior construction;

Fig. 3 is a vertical longitudinal sectional view taken on line 3—3 of Fig. 2;

Fig. 4 is a vertical transverse sectional view taken on line 4—4 of Fig. 2, parts being broken away; and

Fig. 5 is an enlarged fragmentary detail view showing the means for providing an opening between the table frame and top.

Referring to the drawings, the numeral 8 designates a table top, 9 the body or compartment portion which is formed in part of side panels 10, 11 the supporting legs, and 12 the stretcher or lower brace member which connects the lower portions of the legs together. The table may be of any desired shape, and in the form shown, the legs extend upwardly to the top and the side panels are interposed therebetween, and with the exception of the front panel 10', are rigidly connected to the legs.

The table top 8 is hinged at its rear edge portion to the body of the table to swing upwardly, as indicated by dotted lines in Fig. 4, to permit access to the interior portions of the radio apparatus. A two part brace member 13 holds the top in open position. The front portion of the top is provided with one or more depending fastening members 14 which are adapted to fit within clip-members 15 (see Fig. 5) when the top is closed to hold the top slightly above the table frame. This provides a space 16 through which sound vibrations may come forth, and through which air may circulate to carry away heat from the receiver.

Within the compartment portion 9 are spaced apart transverse partitions 17 which have their upper edges formed with a recess 18 (see Fig. 4). Positioned between said partitions, and having its side portions secured thereto, is a baffle board 19 having a curved rear portion 20. Extending around and upwardly from said curved portion, and also extending for a distance along the sides 10 of the baffle board is a fence 21. The said fence has a portion 22 at the rear of the table, of considerable height, and said height decreases toward the sides as at 23 (see Figs. 3 and 4).

15 The receiver 24 is adapted to be mounted on resilient legs 25, constructed preferably of rubber and carried by the baffle board. Spacer blocks 26, extending inwardly from the ends of the fence are adapted to engage 20 the sides of the receiver to position the same. Other spacer blocks 27 are positioned adjacent an opening 28 for the loud speaker 29. When the receiver is in position on the supporting legs 25, its rear portion fits 25 against the spacer blocks 27, as shown by the dotted lines in Fig. 4, and the set being elevated by the legs, overlaps the flanged portion of the speaker as at 30. This permits a very compact construction.

30 The front panel 10' is hinged to the front lower edge of the baffle board 19 or to any other desirable portion of the frame, to permit it to swing downwardly to open horizontal position as shown. A supporting arm 31 35 engaging the panel and the body of the table supports said panel when in open position. Behind the panel 10' is an inner panel 32 which is formed with an opening 33 for exposing the controls and dial of the receiver.

40 It will be noted from Fig. 2 that large openings 34 are provided between the partitions 18 and the side panels 10. Smaller openings 35 are provided on the outer side of the fence 21, and other openings 36 are 45 provided between the sides of the baffle board and the partitions near the front of the table.

It is also to be noted that the loud speaker is so carried by the baffle board that the sound 50 vibrations will be directed downwardly by the speaker toward the floor from the proper height to assure true tone value. If the speaker were supported too close to the floor, the tone would be distorted, and if it were 55 positioned too far away the beneficial results caused by directing the vibrations toward the floor would be lost.

When the radio is being operated, the majority of sound vibrations are emitted from 60 the front of the speaker and said vibrations are directed downwardly through the opening 28. However, other vibrations come forth from the rear of the speaker, and it is found that in ordinary radio cabinets said vibrations frequently meet the vibrations coming

from the front and interfere with or neutralize the latter, thereby impairing the tone quality. In this improved radio table, however, the vibrations emitted by the rear of the speaker are separated by the baffle board 19 from the vibrations emitted by the front of the speaker. By employing the improved baffle board with the fence 21, the sound vibrations coming from the rear of the speaker are caused to travel over a comparatively long path before emerging, and therefore they will not cause interference. The majority of said sound vibrations will travel over the low side portions 23 of the fence, through the recesses 18 of the partitions 17 and out through the large openings 34 between the partitions and the side panels 10. Other of the sound vibrations emitted from the rear of the speaker will pass over the high portion of the fence 21 and out through the openings 35. Still other vibrations will travel out through the openings 36 and through the opening 16 between the top and the table frame. Thus all of the vibrations coming from the rear of the speaker will be forced to travel over a comparatively long path and as a result there will be no interference with the sound vibrations emitted by the front of the speaker and a tone of exceptional quality and volume will result.

It will readily be seen that the elevation of the receiver by the resilient legs 25, in addition to permitting the overlapping of the edge of the speaker, prevents vibrations caused by the speaker from impairing the operation of the set. It will further be seen that by having the top 8 spaced from the frame to provide the opening 16, a complete circulation of air from the bottom to the top of the compartment 9 is permitted, to carry away heat from the receiver tubes.

Although only one form of the invention has been shown and described, it is not desired to be limited to the particular showing, as the broad concept of the invention includes all changes and modifications as may fairly come within the scope of the claims.

What I claim is:

1. In a radio table, a baffle board positioned below and spaced from the top of the table for supporting a loud speaker, said baffle board having an opening therein for directing the sound vibrations emitted from the front of said loud speaker downwardly, and means in connection with said baffle board for causing the sound vibrations emitted from the rear of the loud speaker to travel over a relatively long path before said latter vibrations are permitted to intermingle with the former.

2. In a radio table, a baffle board positioned below and spaced from the top of the table for supporting a loud speaker, said baffle board having an opening therein for directing the sound vibrations emitted from

5 the front of said loud speaker downwardly, and a fence surrounding a portion of said baffle board for causing the sound vibrations emitted from the rear of the loud speaker to travel over a relatively long path before said latter vibrations are permitted to intermingle with the former.

10 3. In a radio table, a baffle board positioned below and spaced from the top of the table for supporting a loud speaker, said baffle board having an opening therein for directing the sound vibrations emitted from the front of said loud speaker downwardly, and a fence surrounding a portion of said baffle board for causing the sound vibrations emitted from the rear of the loud speaker to travel over a relatively long path before being freed so that said latter sound vibrations will not interfere with the sound vibrations emitted from the front of the loud speaker, said fence being high in the rear and decreasing in height toward the sides of the baffle board.

15 4. In a radio table, a baffle board positioned below and spaced from the top of the table for supporting a loud speaker, there being spaces between the sides of the baffle board and the sides of the table and said baffle board having an opening therein for directing the sound vibrations emitted from the front of said loud speaker downwardly, and means in connection with said baffle board for causing the majority of the sound vibrations emitted from the rear of the loud speaker to travel through said spaces between the sides of the baffle board and the sides of the table so that said latter sound vibrations will not interfere with the sound vibrations emitted from the front of the loud speaker.

20 5. In a radio table, a baffle board positioned below and spaced from the top of the table for supporting a loud speaker, there being spaces between the sides of the baffle board and the sides of the table and said baffle board having an opening therein for directing the sound vibrations emitted from the front of said loud speaker downwardly, and a fence surrounding a portion of said baffle board for causing the majority of the sound vibrations emitted from the rear of the loud speaker to travel through said spaces between the sides of the baffle board and the sides of the table so that said latter sound vibrations will not interfere with the sound vibrations emitted from the front of the loud speaker.

25 6. In a radio table, a baffle board positioned below and spaced from the top of the table for supporting a loud speaker, there being spaces between the sides of the baffle board and the sides of the table and said baffle board having an opening therein for directing the sound vibrations emitted from the front of said loud speaker downwardly, and a fence surrounding a portion of said baffle board for causing the

30 majority of the sound vibrations emitted from the rear of the loud speaker to travel through said spaces between the sides of the baffle board and the sides of the table so that said latter sound vibrations will not interfere with the sound vibrations emitted from the front of the loud speaker, said fence having relatively low portions adjacent the said side spaces.

35 7. In a radio table, a pair of spaced apart partitions positioned below the top of the table, there being spaces between said partitions and the sides of the table, a baffle board mounted between said partitions for supporting a loud speaker, said baffle board having an opening therein for directing the sound vibrations emitted from the front of said loud speaker downwardly, and means in connection with said baffle board for causing sound vibrations emitted from the rear of the loud speaker to travel over said partitions to the spaces on the sides thereof so that said latter sound vibrations will not interfere with the sound vibrations emitted from the front of the loud speaker.

40 8. In a radio table, a pair of spaced apart partitions positioned below the top of the table, said partitions having upper edge recesses and there being spaces between said partitions and the sides of the table, a baffle board mounted between said partitions for supporting a loud speaker, said baffle board having an opening therein for directing the sound vibrations emitted from the front of said loud speaker downwardly, and means in connection with said baffle board for causing sound vibrations emitted from the rear of the loud speaker to travel through the recesses of said partitions to the spaces on the sides thereof so that said latter sound vibrations will not interfere with the sound vibrations emitted from the front of the loud speaker.

45 9. In a radio table, a baffle board having a curved rear portion, said baffle board being positioned below and spaced from the top of the table for supporting a loud speaker, there being spaces between the sides of the baffle board and the sides of the table and said baffle board having an opening therein for directing the sound vibrations emitted from the front of said loud speaker downwardly, and a fence surrounding the curved portion of the baffle board for causing the majority of the sound vibrations emitted from the rear of the loud speaker to travel through said spaces between the sides of the baffle board and the sides of the table so that the latter sound vibrations will not interfere with the sound vibrations emitted from the front of the loud speaker.

50 10. A radio table having a top, means positioned below said top for supporting a radio receiving apparatus and a loud speaker, and means on the frame engageable with said top when the latter is closed for causing a space between said top and the table frame through

- which sound vibrations may emerge and through which air may circulate to carry away heat generated by the receiving apparatus.
5. 11. In a radio cabinet, a baffle board for supporting a loud speaker, said baffle board having an opening therein for directing the sound vibrations emitted from the front of said loud speaker outwardly, and a fence positioned laterally from and partially surrounding the baffle board opening for causing the sound vibrations emitted from the rear of the loud speaker to travel over a relatively long path before being freed, so that said latter 10 sound vibrations will not interfere with the sound vibrations emitted from the front of the loud speaker, said fence ultimately directing the sound vibrations emitted from the rear of the loud speaker outwardly in the same direction as the sound vibrations emitted from the front of the loud speaker.
12. In a radio table, a pair of spaced apart partitions positioned below the top of the table, there being spaces between said partitions and the sides of the table, a baffle board mounted between said partitions for supporting a loud speaker, said baffle board having an opening therein for directing the sound vibrations emitted from the front of the loud speaker downwardly, sound vibrations emitted from the rear of the loud speaker traveling over said partitions to the spaces on the sides thereof so that the latter sound vibrations will not interfere with the sound 35 vibrations emitted from the front of the loud speaker.
13. In a radio table, a pair of spaced apart partitions positioned below the top of the table, there being spaces between said partitions and the sides and top of the table, a baffle board mounted between said partitions for supporting a loud speaker, said baffle board having an opening therein for directing the sound vibrations emitted from the front of the loud speaker downwardly, sound vibrations emitted from the rear of the loud speaker traveling over said partitions to the spaces on the sides thereof so that the latter sound vibrations will not interfere with the sound 50 vibrations emitted from the front of the loud speaker.
14. In a radio table, a pair of spaced apart partitions positioned below the top of the table, there being spaces between said partitions and the sides of the table and said partitions having openings therein, a baffle board mounted between said partitions for supporting a loud speaker, said baffle board having an opening therein for directing the sound vibrations emitted from the front of the loud speaker downwardly, sound vibrations emitted from the rear of the loud speaker traveling through the openings of said partitions to the spaces on the sides thereof 65 so that the latter sound vibrations will not interfere with the sound vibrations emitted from the front of the loud speaker.
15. A radio table having a frame and a compartment therein, means for supporting a radio receiving instrument within said compartment, closure means for said compartment, and means in connection with the table frame engageable with said closure means when the latter is in closed position for spacing the latter from the frame to provide an outlet for heat generated by the receiving apparatus.
16. A radio table having a frame and a compartment therein, means for supporting a loud speaker within said compartment, closure means for said compartment, and means in connection with the table frame engageable with said closure means when the latter is in closed position for spacing the latter from the frame to provide an outlet for sound vibrations.
17. In a radio table, a baffle board for supporting a loud speaker so that the axis of the vibrating member thereof is directed downwardly toward the floor, said board being positioned between the table legs, and below the table top and being spaced from the floor a sufficient distance so that the sound vibrations from the loud speaker will be directed downwardly and laterally through said space.
18. In a radio cabinet, a baffle board for supporting a loud speaker, said baffle board having an opening therein for directing the sound vibrations emitted from the front of the loud speaker outwardly, a partition adjacent said baffle board positioned laterally from the loud speaker opening, there being a space between said partition and the side of the table which communicates with the exterior, sound vibrations emitted from the rear of the loud speaker traveling over said partition to the space on the side thereof, so that the latter sound vibrations will not interfere with the sound vibrations emitted from the front of the loud speaker.
19. In a radio cabinet, a baffle board for supporting a loud speaker, said baffle board having an opening therein for directing the sound vibrations emitted from the front of the loud speaker outwardly, a pair of partitions adjacent opposite sides of said baffle board positioned laterally from the loud speaker opening, there being spaces between said partitions and the sides of the table which communicate with the exterior, sound vibrations emitted from the rear of the loud speaker traveling over said partitions to the spaces on the sides thereof, so that the latter sound vibrations will not interfere with the sound vibrations emitted from the front of the loud speaker.
20. In a radio cabinet, a baffle board for supporting a loud speaker positioned below the top of the table, said baffle board having

an opening therein for directing the sound vibrations emitted from the front of the loud speaker downwardly, a partition adjacent said baffle board, there being a space between said partition and the side of the table which communicates with the exterior, sound vibrations emitted from the rear of the loud speaker traveling over said partition to the space on the side thereof, so that the latter sound vibrations will not interfere with the sound vibrations emitted from the front of the loud speaker.

21. In a radio table, a baffle board located beneath and spaced from the table top and having an opening, and a loud speaker mounted upon said board and positioned to direct sound waves downwardly through said opening and toward the floor, there being another opening provided for directing sound waves away from the rear of said speaker remote from said first mentioned opening.

22. In a radio cabinet, a table top, a baffle board located beneath said top and having an opening, side walls coacting with said board laterally of the space between said top and said board, and radio apparatus comprising a loud speaker positioned within said space to direct sound waves downwardly through said opening, there being another opening provided for directing sound waves delivered from the rear of said speaker away from said space and said table top being spaced from the upper edge of at least one of said walls to provide for circulation of air through said space.

In testimony whereof, I affix my signature.

LOUIS SEUTTER.
